OVEN

Edwin P. Van Sciver, Philadelphia, Pa., assignor to Philco Corporation, Philadelphia, Pa., a corporation of Pennsylvania

Application March 5, 1958, Serial No. 49,901

Term of patent 14 years

(Cl. D81—26)

FIG. 1.

FIG. 2.

FIG. 3.

Figure 1 is a perspective view of an oven showing my new design;

Figure 2 is a side view of said oven; and

Figure 3 is an enlarged fragmentary view illustrating a detail shown at the top of Figure 1.

The side of the oven not illustrated in the drawing is generally similar to the side shown. The back of the oven is plain.

My design for an L-shaped oven is characterized by the two windows, arranged as shown.

I claim:

The ornamental design for an oven, substantially as shown and described.
